Inventor

William E. Richards

UNITED STATES PATENT OFFICE.

WILLIAM E. RICHARDS, OF HOHOKUS, NEW JERSEY.

HANDLE FOR TOOLS AND IMPLEMENTS.

1,322,618.

Specification of Letters Patent. Patented Nov. 25, 1919.

Application filed April 9, 1917, Serial No. 160,701. Renewed April 14, 1919. Serial No. 290,077.

To all whom it may concern:

Be it known that I, WILLIAM E. RICHARDS, a citizen of the United States, residing at Hohokus, county of Bergen, and State of New Jersey, have invented certain new and useful Improvements in Handles for Tools and Implements, of which the following is a specification.

My invention relates to handles for tools and implements, and has for its object to construct the same so that it may be produced in an exceedingly simple and inexpensive manner, and so that it will be thoroughly efficient and practical in use; to 10 so form the same that when used with geared driving mechanism a yielding support will be formed for some of the driving elements, so that the parts of the said mechanism will accommodate themselves to each 15 other at all times, and a smoother and easier running mechanism will be produced than heretofore usual in this class of articles; also to provide simple and efficient means of attachment for such driving mechanism or other parts with which the handle 20 is to be used.

These, and other objects of my invention, are set forth in the following specification, and illustrated in the accompanying drawings, the particular features of novelty 30 which constitute my invention being pointed out in the claims at the end hereof.

In the drawings, which form a part of this specification, and in which similar letters and figures of reference refer to similar parts wherever they occur:—

Figure 1 is a front elevation of one of my handles, partly in section, showing it as used with an egg-beater;

Fig. 2 is a side elevation of the handle shown in Fig. 1;

Fig. 3 and 4 are respectively front and side elevations of a modified form of my handle, the first being partly in section.

In order that I may more clearly define my invention I have shown it in Fig. 1 as applied to an egg-beater, and I will now proceed to describe it accordingly.

In forming my handle I take a strip of flat, sheet metal, of appropriate size and gage, and bend it at its central portion 1, to form a looped handle portion 2, with the arms 3, 4, projecting outwardly therefrom in substantially parallel planes.

The arms 3, 4, are brought together at a

point adjacent to the handle portion 2, to form a handle extension 5, the two arms being rigidly secured together at this point by rivets, or in any other desired manner.

Beyond the handle extension 5, the arms 60 3, 4, are bent away from each other at 6, to form a fork 7, the extreme ends 8, 8, of the said arms being left free and unconnected.

The fork 7 is adapted to receive and hold an operating handle 9, bearings 10, 11, being 65 formed in said arms for this purpose, and also a driving wheel 12, which is mounted on, and adapted to be rotated by said handle 9.

At the extreme outer end of the fork 7 the 70 arms are bent outwardly from the sides of the fork to form retaining flanges 13, 14, additional flanges 15, 16, being pressed out of the sides of said arms at a little distance from the flanges 13, 14.

The flanges above-named serve to support and retain the beater members and driving pinions in operative position.

The beater members comprise beating elements 17, 18, and driving pinions 19, 20, 80 which are rotatably mounted on a wire loop 21, the ends of which form shafts for said pinions to operate upon, the ends of the wire loop being secured to the handle by passing said ends through openings 22 in said 85 flanges 13, 15, and 14, 16, and then upsetting the wire between said flanges, so that said ends will be rigidly held by said flanges.

In Figs. 3 and 4 I show a modified form 90 of my handle in which the retaining flanges on the outer ends of the arms 3, 4, are formed and arranged in a different manner.

In this construction, instead of pressing the flanges 15, 16, out of the sides of the arms, as shown in Figs. 1 and 2, I bend the 95 arms outwardly, as at 23, to form the flanges 15, 16, and then bend the said arms around upon themselves as at 24, to form returning flanges 25, 26, and form openings 22 in said flanges for the ends of the wire loop 21, 100 or other element that is to be secured thereto.

It will be obvious, that as the ends of the arms 3, 4, are free and unconnected, and as the handle is formed of thin, flat, sheet metal, which possesses an inherent springy 105 nature, that the ends of said arms form an elastic, yielding support for the driving pinions, allowing them sufficient lateral movement so that they will accommodate themselves at all times to the thrust of the driv- 110

ing wheel, while still being sufficiently rigid to co-act properly therewith.

This is important in such structures as egg-beaters and similar articles, where the driving gear is usually cast, and meshes more or less imperfectly, and does not work smoothly. My construction produces an easier and smoother running structure than any other of which I am aware.

10 While I have described my invention as applied to an egg-beater, I do not confine myself to such an application.

What I claim as new and desire to secure by Letters Patent is:—

15 1. A handle comprising a looped handle portion having two arms projecting therefrom in substantially parallel planes, a fork formed by the outer ends of said arms, and a plurality of retaining flanges formed upon the extremities of each of said arms.

20 2. A handle comprising a looped handle portion having two arms projecting therefrom in substantially parallel planes, a fork formed by the outer ends of said arms, the extremities of said arms being bent outwardly to produce one set of flanges, and

then bent inwardly to form returning flanges.

3. A sheet metal handle bent at its central portion to form a looped handle portion having two arms projecting therefrom in substantially parallel planes, a fork formed by the outer ends of said arms, and a plurality of flanges formed upon the outer sides of said fork.

35 4. A sheet metal handle bent at its central portion to form a looped handle portion having two arms projecting therefrom in substantially parallel planes, a fork formed by the outer ends of said arms, the outer extremities of said fork being first bent outwardly, and then inwardly, to form retaining flanges.

In testimony whereof, I have signed my name to this specification in the presence 45 of two subscribing witnesses, this 7th day of April, 1917.

WILLIAM E. RICHARDS.
